REVERSING MECHANISM FOR SKIDS OF PAPER

Grover Cleveland Mutchler, Easton, Pa.

Application August 1, 1946, Serial No. 687,603

5 Claims. (Cl. 214—1)

1

The invention relates to a method of handling skids of paper, particularly paper coming from a press and printed on one side only, and to improved mechanism for reversing such skids of paper.

In the printing industry, and particularly in connection with automatic sheet fed machines, sheets of paper coming from a press and printed on one side only are delivered from the press and arranged in a pile on a skid with the printed side up. Before the unprinted sides of the sheets can be printed the sheets must be reversed, and under present conditions this is a very laborious operation, necessitating repeated handling of the sheets. It is the object of my invention to provide turning means for reversing the entire pile of papers as a unit so that the unprinted sides of the sheets may then be delivered to a press for completion of the printing operation. A similar procedure is desirable in connection with the folding of sheets of paper.

The reversing operation is accomplished in accordance with my invention by the use of a turning device equipped with two sets of slideable lifting and holding fingers adapted to initially lift the pile to a position for turning and then to firmly engage the pile both at the top and bottom thereof so as to hold the papers firmly in position during the turning movement. The turning device is mounted for rotation about a horizontal axis through an angle of 180° so as to completely reverse the pile as a whole, after which the sets of lifting and holding fingers are separated and the pile lowered to a position where it may be carried by an ordinary transfer truck for further printing or folding.

The invention will be more readily understood by reference to the accompanying drawings and the following detailed description, which are intended as illustrative of the inventive thought rather than as limiting the invention to the precise details set forth therein.

In the drawings:

Figs. 1 to 5 are side elevational views of the turning device largely diagrammatic in character showing successive steps in the holding and reversing of a pile of papers in accordance with my invention.

Fig. 6 is an end view of the turning device in a position corresponding to that diagrammatically indicated in Fig. 2, the pile being represented in dash lines;

Fig. 7 is a top plan view of the same;

Fig. 8 is a longitudinal sectional view on line 8—8 of Fig. 9;

2

Fig. 9 is a horizontal sectional view of the turning device on line 9—9 of Fig. 8;

Fig. 10 is a transverse sectional view on line 10—10 of Fig. 8 looking in the direction of the arrows;

Fig. 11 is a horizontal section on line 11—11 of Fig. 8;

Fig. 12 is a detail taken on line 12—12 of Fig. 10;

Fig. 13 is a detail taken on line 13—13 of Fig. 10 showing a reversing pinion;

Fig. 14 is a further detail view of the reversing pinion and associated mechanism taken on line 14—14 of Fig. 10; and

Fig. 15 is a detail view similar to Fig. 13 but with the turning device reversed 180° from the position indicated in Fig. 13.

Referring more in detail to the drawing A represents generally my improved reversing or turning machine, shown in Fig. 1 as supporting thereon a pile of papers B to be reversed or turned printed side down. The pile of papers may be delivered to the turning machine by means of an ordinary transfer truck or the like. The pile B may be supported upon a skid C of any suitable construction, better shown in Fig. 6, and having four depending legs. A similar skid indicated at C' is placed upside-down upon the top of the pile after the pile has been delivered to the machine.

In operation the pile with skids C and C' at the bottom and top thereof, respectively, is then clamped between a pair of movable fingers as illustrated in Fig. 2, the lower set of fingers holding the skid C and the upper set of fingers holding the skid C' and being moved to intermediate positions as shown in Fig. 2, whereupon the entire pile is reversed 180° through the steps indicated in Figs. 3 and 4, after which the holding fingers are separated and the pile B lowered to the position indicated in Fig. 5, the skid C being then uppermost and the skid C' being lowermost. The upper skid C is then removed and the pile may be delivered to a press or folding machine by means of an ordinary lift truck or the like.

As shown, the turning machine A is provided with a floor or base 10 having a pair of longitudinal grooves 11 formed therein as indicated in Figs. 8, 9, 10 and 11. The base 10 is provided with a pair of triangular side pieces 12 carrying horizontal pivots 13, 13 for the turning member or pile carrier 14 which is adapted to support the stack B and to be turned about the pivots 13, 13 through a 180° angle.

The turning member or carrier 14 comprises a normally vertical reversible backing member 15 against which one side or vertical edge of the

stack is positioned, which backing member is provided with upper and lower sets of parallel slots 16 and 17 for two sets of fingers 18 and 19, respectively.

Extending from the opposite sides of the plate 15 are semicircular rack members 20, 20 provided with teeth 21 which are adapted to be engaged by a suitable gear or gears 22 as illustrated in Figs. 10, 13, 14 and 15, the gear or gears being adapted to be driven by one or more motors 23 through suitable intermediate gearing 24. The motor 23 is of the reversible type and may be operated to turn the reversing member 14 through an angle of 180°. Preferably one gear 22 is provided for each member, the two gears being connected by a transverse shaft (not shown).

As clearly shown in Fig. 8 the fingers 18 and 19 are carried by plates 25 and 26, the ends of which plates are slideable in grooves 28 formed in side bars 29 attached to the front plate 15, see Figs. 9 to 12. The slideable plates 25 and 26 are adapted to be actuated toward or from each other by two sets of sprocket chains 30 and 31 (Figs. 8 and 10), to which chains the plates are attached. As shown the sprocket chains 30 run over upper and lower sprockets 32 and 33 carried by shafts 34 and 35, respectively, having their ends mounted in the side bars 29. The sprocket chains 31 are similarly provided with sprockets 36 and 37 carried on shafts 38 and 39, respectively, said shafts also having their ends mounted in the side bars 29. In the construction shown the shaft 39 is driven by a suitable reversible motor 40 through intermediate gearing 41. In the arrangement shown the two sets of sprocket chains 30 and 31 are driven from the same source of power. To this end the shafts 35 and 39, driving the upper and lower sets of sprocket chains 30 and 31, respectively, are interconnected at their opposite ends by suitable gearing 42.

Reference has been made to the skids C and C' which are adapted to be placed one at the bottom and the other at the top of the pile B to be reversed. These may be of any desired construction, but according to the preferred embodiment each comprises a base plate 50 having a pair of metal straps 51 extending along the longitudinal edges thereof, each strap having a pair of loops 52 at the ends thereof to provide legs for the skids, there being four such legs in all for each skid, one at each of the four corners of the base plate. The fingers 18 and 19 of the reversing mechanism when in the holding position are adapted to engage the skids across the straps 51 intermediate the pairs of legs 52.

Movement of the reversing or turning member or carrier 14 may be limited to 180° by engagement of opposite end portions 55 and 56 of the plate 15 with a fixed abutment which may be part of a bracket 57 which carries gear 22 engaging the teeth 21 on the semi-circular rack 20.

The operation of the device will be apparent from the foregoing description. Assuming the reversing mechanism A to be in the position shown in Fig. 1 a pile of paper B carried upon a skid C, which paper may be printed on the upper surface as indicated in Fig. 9, is brought to the turning device A by means of a suitable truck. The skid and pile of paper resting thereon are placed on the floor or base 19 of the reversing mechanism over the lower set of fingers 19, which fingers are embedded in grooves 11 so as to be flush with the surface of the floor. In such position the fingers 19 extend between the pairs of legs 52 of the skid C. The other skid C'

is now placed on top of the pile B with the legs 52 thereof extending upwardly. The fingers 18 and 19 are then actuated through the motor 40, sprocket chains 30 and 31, and carrying plates 25 and 26 to simultaneously raise the lower fingers 19, carrying with them the pile of papers B with upper and lower skids C and C', and at the same time lowering the fingers 18 until they engage the top of the pile and hold the same securely in position, as indicated in Figs. 2 and 8. It will be noted that in this position the fingers 18 and 19 are equally distant from their respective ends of the plate 15. The finger actuating motor 40 is then stopped and the carrier reversing motor 23 is then actuated to swing the carrier or turning mechanism 14 180° through the horizontal position indicated in Fig. 3 to the reversed vertical position shown in Fig. 4 where the carrier 14 is stopped by engagement of the plate extension 55 with the bracket 57 carrying gear 22, or with the gear itself. The motor 23 is then stopped either automatically or manually.

The motor 40 is then again actuated to separate the sets of fingers 18 and 19 carried by the sliding plates 25 and 26, thereby simultaneously lowering the pile carried by the fingers 18 and the floor and raising the other set of fingers 19 so that the pile may then be taken by means of a truck or other suitable means to a press or folding machine, where additional operations are to be performed on the individual papers in the reversed pile B. Where the reversal of the pile is for the purpose of completing a printing operation it will be apparent that the printed sides of the papers are now facing downwardly and the unprinted sides are facing upwardly, so that the individual papers on the pile are now adapted for such further operations as it may be desirable to perform.

The invention has been described in detail for the purpose of illustration, but it will be obvious that numerous modifications and variations may be resorted to without departing from the spirit of the invention. Thus, it will be apparent that any suitable means may be employed for performing the reversing operation and for moving the fingers 18 and 19 toward and away from each other. Likewise, any suitable means may be employed for limiting the reversing movement to 180°. The semicircular racks 20 may both be provided with gear teeth each engaged by suitable reversing gears and driven from the same or separate sources of power. Other modifications and variations which will be apparent to those skilled in the art may be resorted to without departing from the spirit of the invention. Instead of providing gear teeth on the semicircular members sprocket chains or the like may be provided on the arcuate surfaces of said members each engageable by suitable gears or sprockets.

Another arrangement for driving the carrier 14 is to provide gears 22, one for each rack member 20, which gears may be interconnected through intermediate gearing and interconnecting shaft extending through the base of the machine.

I claim:

1. An apparatus for reversing piles of paper in bulk, comprising a fixed base, a pair of spaced side members supported by the base, a pile carrier mounted between said side members for rotation through an angle of 180° with reference to the base and side members, said carrier including a reversible normally vertical backing member, a

pair of vertically spaced pile holding members slidably mounted on the carrier and projecting outwardly from the backing, said holding members being adapted to serve alternately as top and bottom supports for the pile depending on the position of the carrier, means for positively moving said members toward or away from each other and with reference to said backing member to raise or lower the pile and to grip or release the pile, means for actuating the carrier to reverse the same together with the spaced holding members and the pile carried thereby, and means for limiting the swinging movement in either direction.

2. An apparatus for reversing piles of paper in bulk, comprising a fixed base, a pair of spaced side members supported by the base, a pile carrier mounted on said side members for rotation through an angle of 180° with reference to the base and side members, said carrier including a reversible normally vertical backing member, a pair of vertically spaced pile holding members slidably mounted on the carrier and projecting outwardly from the backing, said holding members being adapted to serve alternately as top and bottom supports for the pile depending on the position of the carrier, means for positively moving said members toward or away from each other and with reference to said backing member to raise or lower the pile and to grip or release the pile, means for actuating the carrier to reverse the same together with the spaced holding members and the pile carried thereby, and means for limiting the swinging movement in either direction, said backing member having slots therethrough to permit passage of said pile holding members.

3. An apparatus for reversing piles of paper in bulk comprising a stationary base member having a pair of floor portions upon either of which a pile of paper may be deposited before or after reversal, a pair of spaced side members carried by said base member, a pile carrier between said side members for reversal through an angle of 180°, means for actuating said carrier to reverse the same and means for limiting the swinging movement of the carrier in either direction, said carrier including a normally vertical backing member against which one side of a pile of paper is adapted to be positioned, said backing member extending between the two side members, and separating the two floor portions of said base, a pair of vertically spaced pile holding means slidably mounted with reference to said backing member and projecting outwardly therefrom, said holding members being adapted to alternately engage the top or bottom of the stack depending on the position of the carrier, and means for positively moving said holding members toward or away from each other, and with reference to

the backing member, whereby the pile is raised or lowered and gripped or released by said holding members.

4. An apparatus for reversing piles of paper in bulk comprising a stationary base member having a pair of floor portions upon either of which a pile of paper may be deposited before or after reversal, a pair of spaced side members carried by said base member, a pile carrier between said side members for reversal through an angle of 180°, means for actuating said carrier to reverse the same and means for limiting the swinging movement of the carrier in either direction, said carrier including a normally vertical backing member against which one side of a pile of paper is adapted to be positioned, said backing member extending between the two side members, and separating the two floor portions of said base, a pair of vertically spaced pile holding means slidably mounted with reference to said backing member and projecting outwardly therefrom, said holding members being adapted to alternately engage the top or bottom of the stack depending on the position of the carrier, and means for positively moving said holding members toward or away from each other, and with reference to the backing member, whereby the pile is raised or lowered and gripped or released by said holding members, said holding members each comprising a pair of spaced fingers, and said backing members having slots to permit passage of said fingers therethrough.

5. A pile reversing device comprising a pile carrier mounted for rotation about a horizontal axis through an angle of 180°, said carrier including a normally vertical backing member, upper and lower pile engaging and elevating members, each movable toward and away from the other, slideable with reference to the backing member and projecting outwardly therefrom in the same direction, means for simultaneously actuating both of the pile engaging and elevating members to engage or release the pile and to raise or lower the same, and means for actuating the carrier as a whole, including the backing member, to reverse the pile.
